CHARLES E. PRÉTAT:

BY
H. W. Smith, Jr.
ATTORNEY

UNITED STATES PATENT OFFICE.

CHARLES E. PRÉTAT, OF WATERBURY, CONNECTICUT.

DESIGN FOR A SPOON.

SPECIFICATION forming part of Design No. 22,527, dated June 13, 1893.

Application filed May 12, 1893. Serial No. 474,029. Term of patent 14 years.

To all whom it may concern:

Be it known that I, CHARLES E. PRÉTAT, a citizen of the United States, residing at Waterbury, in the county of New Haven and State of Connecticut, have invented and produced a new and original Design for the Ornamentation of Handles for Spoons, Knives, Forks, &c.; and I do hereby declare the following to be a full, clear, and exact description of the invention, such as will enable others skilled in the art to which it appertains to make and use the same.

The accompanying drawing is an elevation illustrating my design as applied to the handle of a spoon.

The leading features of my new and original design are, the uniformly curved parallel threads running along the borders of the lower part of the handle, and terminating at the bottom in diverging foliate patterns and at the top in converging scroll work; and the uniformly curved threads running along the borders of the upper part of the handle and terminating at the bottom in scroll work which meets the scroll work on the lower part of the

handle and at the top in scroll work which is surmounted at the head of the handle by irregular scrolls.

In the drawing, 1 is the lower part of the handle having along its borders the uniformly curved parallel threads 2, 3 the foliate patterns at the bottom of said threads, 4 the converging scroll work at the top thereof. Referring to the upper part 5 of the handle, 6 are the uniformly curved parallel threads 30 along the borders, 7 the scroll work at the bottom which meets the scroll work 4, 8 the scroll work at the top of these threads, and 9 the irregular scrolls at the head of the handle. 35

I claim—

The design for the handle of a spoon, or similar article, substantially as shown in the accompanying drawing.

In testimony whereof I affix my signature in presence of two witnesses.

CHARLES E. PRÉTAT.
